UNITED STATES PATENT OFFICE

MAX SEIDE, OF DETROIT, MICHIGAN, ASSIGNOR TO CHAMBERLIN METAL WEATHER-
STRIP CO., OF DETROIT, MICHIGAN, A CORPORATION OF MICHIGAN

ROLLER SCREEN

Application filed March 21, 1929. Serial No. 348,719.

This invention relates to roller screens and the object of the invention is to provide a roller screen for steel casement windows including a frame adapted for attachment to the window and provided with ways in which the screen is adapted to ride.

Another object of the invention is to provide a roller screen and frame adapted for attachment to a window without interfering with the normal use of the window and adapted to be rolled up out of sight when not in use.

A further object of the invention is to provide an arrangement whereby a pressure is maintained on the edges of the screen to hold the screen taut across the window opening and to prevent the entrance of insects thereabout.

Another object of the invention is to provide a roller screen including a frame adapted for attachment to a window and arranged so that the screen is supported by the frame independently of the window.

These objects and the several novel features of the invention are hereinafter more fully described and claimed and the preferred form of construction by which these objects are attained is shown in the accompanying drawings in which—

Fig. 1 is an elevation of a window of the steel casement type equipped with my improved roller screen.

Figs. 2 and 2a are enlarged sections taken on lines 2—2 and 2a—2a of Fig. 1.

Fig. 3 is a perspective view of one end cap for the roller housing.

Fig. 4 is an enlarged section taken on line 4—4 of Fig. 1.

Fig. 5 is a section taken on line 5—5 of Fig. 4.

In the window illustrated in the drawings in Figs. 1 and 2 a pair of vertical mullions 1 and 2 are provided and a horizontal mullion 3 is provided across the top. The central window frame 4 is mounted on the mullions 1 and 2 and the hinged window 5 is hinged to the frame 4 to close the opening in the frame 4 as shown in Fig. 2. Window lights are also provided about the exterior of these mullions 1, 2 and 3 in the particular type of win-

dow shown though the roller screen is not used over these parts of the window due to the fact that they do not open. The device consists primarily of two vertical channel shaped sheet metal frame members 6 each having an inner flange 7 which is apertured and the adjacent mullion is drilled so that these frame members 6 may be bolted to the vertical mullions by the bolts 8 shown in Figs. 2 and 4. The frame members 6 extend upwardly and support the roller housing 9 at the upper end thereof as shown in Figs. 1, 4 and 5. Each frame member 6 is provided with an outer flange 10 having an inturned edge as shown in Fig. 2 and this flange 10 extends upwardly into contact with the lower edge of the housing 9, as shown in Fig. 4, the flange 10 being cut away thereabove as shown in Fig. 5.

The roller housing is provided with an end cap 11 at one end secured to the housing and bolted to the frame members 6 by the bolts 12 and a similar cap is provided at the opposite end of the roller housing which is secured to the roller housing and the frame members 6 in the same manner. The caps are stationarily secured to the housing 9 and the central shaft 13 is provided with a rounded end 14 engaging in the aperture 15 in the cap 11 while the opposite end of the shaft is squared and engages in a cap at the opposite end of the roller housing which is similar to the cap 11 except that it is provided with a square aperture in place of the aperture 15 in which the square end of the shaft 13 engages. This prevents the shaft from rotating. As shown in Fig. 5 a member 17 is rotatably mounted on the shaft 13 and supports the tubular roller 18 and the spring 16 is secured at one end to the member 17 and at the opposite end to the shaft 13. The roller tube 18 is secured to the member 17 and a screen 19 is secured to the shell 18 and is wound thereabout. By this arrangement, as will be understood from Figs. 4 and 5, when the edge of the screen 19 is drawn downwardly the members 17 and 18 are rotated on the shaft 13 thus winding up the spring 16 to increase its tension. Also by this arrangement when the screen is released the spring 16 will roll

the screen 19 up into the housing 9. In order to maintain a tension on the edge of the screen a spring bronze strip 20, shown in Figs. 2 and 4, is riveted to each frame member 6 and 5 is concealed within the channel formed thereby.

These spring bronze strips are each provided with a flange 21 normally contacting the flange 10 of the respective frame member 10 6 and the strips 20 at the upper end, as shown in Fig. 4, are sloped inwardly at 22 so that the screen will readily feed into position between the spring bronze strips and the channel flanges 10. The bronze strip 20, as shown in

15 Figs. 2 and 4, is also provided with a flat flange 24 terminating in a sloping flange 25. These flanges 24 and 25 are merely guide flanges and if the screen should be pushed out of its channel at the edge these flanges

20 24 and 25 provide a surface over which the edge of the screen may be guided back into its channel. The lower edge of the screen is secured in a double channel 23 by means of which the screen may be drawn downwardly

25 between the spring bronze strips and the channel flanges and if desired the tension of the spring bronze strips 20 may be made sufficient to hold the screen in position against the tension of the spring 16 but sufficiently

30 flexible so that by raising the channel edge 23 of the screen the spring 16 will take up the slack in the screen. If desired a latch may be provided at the bottom of the window for engaging the double channel 23 whereby the 35 screen may be held in position to close the opening irrespective of the tension of the spring bronze strips 20. With this roller screen the channels in which the screen is adapted to ride are secured directly to the 40 window frame without interfering with the trim about the window frame.

By this arrangement the wall finish may be carried right up to the window frame without the necessity of providing wooden mouldings or jambs to which screen guides may be secured. It is also to be noted that this device does not interfere with the draperies over the window and as the screen guides are entirely concealed within the frame member 6 a very 45 neat appearance is attained. Also the entire device may be made up as a unit with the roller housing 9 forming the connecting frame member and supported on the vertical frame members.

50 From the foregoing description it becomes evident that the device is very simple and efficient in operation, will not easily get out of order, provides a screen for tightly screening the window opening and provides a device which accomplishes the objects described.

Having thus fully described my invention, its utility and mode of operation, what I claim and desire to secure by Letters Patent of the United States is—

65 1. A roller screen including a housing and

a roll screen therein adapted for mounting on a metal window frame comprising a pair of metal channel members positioned in spaced relation with the channels thereof facing each other, one flange of each channel member being adapted for attachment to a window frame and the other or outer flange of which terminates below the upper end, the roll screen housing having end portions attachable to the said ends of the channel members and having a longitudinal slot in its lower rear edge, the forward edge of which practically coincides with the terminal end of the forward flange, a spring metal member secured to each channel member and having a flange extending practically parallel with the forward flange of the channel member and lying in spring contact therewith, the said spring flange having its upper end outturned to engagement with the rear edge of the slot of the screen housing, said forward flange of the channel and spring flange providing a guide for opposite edges of the screen and the channel flange providing a practically non-yieldable element against which the yieldable spring flange holds the screen when drawn therebetween.

2. A roller screen including a housing and a roll screen therein adapted for mounting on a window frame comprising, a pair of vertically positioned metal channel members in spaced relation with the channels thereof facing each other, the inner flange of each channel member being attachable to the window frame, said housing having end portions attachable respectively to the upper ends of the channel members and extending therebetween and having a longitudinal slot at its rear edge through which the screen may be moved, a spring metal member attachable to each channel member and each having a part lying in yieldable contact with the outer flange of the respective channel member providing therewith a guide for opposite side edges of the screen.

3. A roller screen including a housing and a roll screen member therein for mounting on a window frame comprising, a pair of vertically positioned metal channel members in spaced relation with the channels thereof facing each other, said housing being positioned at the upper end of the channel members, the inner flange of each channel member being attachable to the window frame and the housing having a longitudinal slot therein, the inner edge of which practically coincides with the upper end of the other and outer flange of the channel members, a spring metal member attachable to each channel member and having a part lying in yieldable contact with the outer flange of the respective frame member providing a practically non-yieldable support therefor, the upper end of the spring metal member being outturned to practically coincide with the rear edge of the

5 said slot of the housing, said outer flange of each channel and companion yieldable part of the spring metal member providing a vertical guide extending from the housing to the lower end of the channel members in which the opposite side edges of the screen are held when withdrawn from the housing.

10 4. A roller screen including a housing and a roll screen therein adapted for mounting on a window frame comprising a pair of vertically positioned metal channel members in spaced relation, with the channels thereof facing each other, the inner flange of each channel member being attachable to the window frame, said housing having end portions attachable respectively to the upper ends of the channel members and extending therebetween and having a longitudinal slot at its rear edge through which the screen may be 15 moved, said channel members further being constructed to provide a supporting means for the opposite side edges of the screen.

20 In testimony whereof I sign this specification.
